DESIGN FOR A BRAKE ADJUSTING TOOL

Wilbert F. Schnitger, Waukesha, and Earl C. Southall, Milwaukee, Wis.

Application December 11, 1946, Serial No. 135,495

Term of patent 3½ years

(Cl. D54—13)

To all whom it may concern:

Be it known that we, Wilbert F. Schnitger, a citizen of the United States, residing at Waukesha, in the county of Waukesha and State of Wisconsin, and Earl C. Southall, a citizen of the United States, residing at Milwaukee, in the county of Milwaukee and State of Wisconsin, have invented a new, original, and ornamental Design for Brake Adjusting Tool, of which the following is a specification, reference being had to the accompanying drawing, forming part thereof.

In the drawing:

Fig. 1 is a plan view of a brake adjusting tool, showing our new design;

Fig. 2 is a view illustrating one edge thereof; and

Fig. 3 is a view of the opposite edge.

We claim:

The ornamental design for a brake adjusting tool, substantially as shown.

WILBERT F. SCHNITGER.
EARL C. SOUTHALL.
